UNITED STATES PATENT OFFICE.

BENJAMIN F. JACKSON, OF BOSTON, MASSACHUSETTS, ASSIGNOR TO BOSTON CRUDE OIL BURNER CO., OF BOSTON, MASSACHUSETTS, A CORPORATION OF MAINE.

HYDROCARBON-BURNER SYSTEM.

No. 857,808.

Specification of Letters Patent.

Patented June 25, 1907.

Application filed December 5, 1904. Serial No. 236,426.

To all whom it may concern:

Be it known that I, BENJAMIN F. JACKSON, of Boston, in the county of Suffolk and State of Massachusetts, have invented certain new and useful Improvements in Hydrocarbon-Burner Systems; and I hereby declare that the following is a full, clear, and exact description of the same, reference being had to the accompanying drawings, forming part of this specification.

This invention relates to improvements in systems, or devices, for burning hydro carbon for heating purposes.

One object of the invention is to so construct a hydro carbon burner and its mounting that it can be readily applied to an opening in the fire box of a boiler or furnace.

Another object of the invention is to so construct a hydro carbon burner that the atomizer thereof may be automatically cleared from time to time.

Another object of the invention is to so construct a hydro carbon burner system that the supply of liquid fuel may be automatically controlled.

Another object of the invention is to improve the general construction of hydro carbon burners of the nature herein described.

The invention consists in such peculiar features of construction and combination of parts as shall hereinafter be described and pointed out in the claims.

The drawing represents an elevation, partially in section, of the improved hydro carbon burner system as applied to a furnace, as the furnace or fire box of a steam boiler.

As shown in the drawings A represents a portion of the walls of any well known furnace, as the fire box of a steam boiler, in which it is desired to generate heat for any purpose; B representing an opening in said wall, usually the door opening, and C a baffle plate, or block, designed to deflect the heat of the hydro carbon flame in any desired direction.

Adapted to fit in the opening B is a box of substantial construction and having the inclined wall 5, the top 6 and the bottom 7 connected by sides as 8; this box being designed to form a closure for the opening B, as shown in the drawings, and being furnished with lips as 9 and 10 which prevent the box from being pushed too far within said opening and also close the space between the outer

surfaces of the box and the edge of the opening B. Through an opening in the inclined wall 5 of said box extends the Bunsen tube 11 of the hydro carbon burner which is thereby supported in position by said box. On the tube 11 is mounted the pressure chamber 12 furnished with the tubular compartment 13 having the openings 14—14 and the lower end opening 15 and, within this compartment 13 is located the atomizer tube 16 having the contracted orifice end 17 positioned in the opening of the end 15 of said compartment, the outer end of the atomizer tube 16 extending through an opening in the wall of the chamber 12 and being furnished with the casing 18. In this casing 18 is yieldingly mounted a diaphragm 19 which preferably forms one wall of the liquid fuel conduit 20, so that sudden or undue pressure exerted on the fuel in said conduit will effect the deflection of said diaphragm in one direction. To this diaphragm 19 is secured the clearer needle 21 which extends through an opening in the casing 18 into the tube 16, the end of this needle being positioned close to and approximately in line with the orifice in the end 17, so that under the deflecting action of the diaphragm 19 a portion of the end of this needle may be projected sufficiently into said orifice to effect the clearing thereof of sediment or of foreign matter lodged therein.

In order that the clearer needle 21 may be manually actuated, the stem of the needle is continued through the diaphragm 19 to form the extension 23 which works in the stuffing box 24 of the conduit wall 22. The retraction of the needle 21 being effected by the spring 25 located between a portion of the casing 18 and the diaphragm 19 or, manually, by exerting a retracting strain on the extension 23.

Connecting the conduit 22 with the atomizer tube 16 is the delivery tube 26 which communicates with the interior of the atomizer tube and is of a size suitable for the delivery of liquid fuel thereto. Communicating with the conduit 20 is the fluid fuel supply pipe 27 which is of any suitable length to connect a tank 28 or other source of fluid fuel supply with said conduit. This pipe 27 is preferably furnished with a valve 29, for controlling the supply of fluid fuel, and with the valve seat 30 adjacent to which is the diaphragm chamber 31 furnished with the diaphragm 32 hav-

ing the valve 33 which is adapted to seat itself in the valve seat 30 when moved thereagainst by the deflection of the diaphragm 32.

5 The pressure pipe 34 is designed to be connected with any source of pressure such as air or steam, preferably the latter, and communicates with the pressure chamber 12 and with the upper portion of the tank 28, by the 10 pipe 35, a connection also being made by the pipe 36 between such pressure pipe 34 and the diaphragm casing 31. The flow of the pressure fluid through the pipe 34 being controlled by the valve 37 located between the 15 connection with the diaphragm chamber 31 and the atomizer.

In order that foreign matter, may be excluded from the pipe 27 the end portion thereof within the tank 28 is preferably furnished with a strainer 38 of any usual construction.

It is of course evident that the pipes and conduits may be of any diameter, length and construction suitable for use in connection 25 with devices of this character.

When working under normal conditions a suitable quantity of liquid fuel is forced from the tank by pressure from the pipe, and passes through the conduit 20 and is delivered by the tube 26 to the interior of the atomizer tube 16 from whence it is drawn through the aperture end 17 by the flow of the pressure fluid through the pipe 34, the pressure chamber 12, through the openings 14 in 30 the wall of the compartment 13 and thence out of the open end 15. The liquid fuel passing out of the atomizer tube being atomized and becoming mixed with the pressure medium passes through the Bunsen tube 11, drawing with it a proportion of air, which 35 enters through the perforations in the outer portion of said tube, and is finally subjected to combustion within the furnace, the heat products of the combustion of the gases 40 being deflected in the desired direction by the baffle C.

Should the aperture of the atomizer tube become clogged, a back pressure of the fluid fuel will result and this pressure being exerted on the diaphragm 19 will cause the deflection of the diaphragm and the clearer needle 21 will be forced sufficiently into said aperture to clear the same, the pressure on the diaphragm 19 being then relieved, by the 45 restarting of the flow of the fuel, the spring 25 will be permitted to act to move the diaphragm and its needle backward. This clearance may also be effected manually from time to time by pressing against the extension 23.

The diaphragm 32 is preferably designed to resist deflection under pressure existing, under normal use, in the pipe 34 but is also designed to be deflected toward the valve

seat 30 by undue increase of pressure in said 65 pipe, as by an undue increase of steam pressure when the pipe 34 is connected with the steam supply of the boiler heated by this device, the result of this deflection of the diaphragm 32 being to close the valve 33 against 70 its seat 30 and prevent the flow of the fluid fuel a subsequent reduction of pressure in the pipe 34 permitting the diaphragm 32 to recover its normal position and open the valve for the passage of the fuel. When the valve 75 37 is closed the sudden increase of pressure in the pipe 34 will effect the deflection of the diaphragm 32 and the closing of the valve 33 against its seat, thus preventing the flow of fuel through the pipe 27 and the resultant 80 waste thereof.

It is not my intention to limit myself to the construction herein shown, or to any particular construction, but only as herein claimed.

Having thus described my invention, I 85 claim as new and desire to secure by Letters Patent.

1. A burner comprising an atomizer tube having an apertured end, a casing mounted on said tube, a flexible diaphragm in said 90 casing, a clearer needle movably mounted in the tube and designed to be actuated by said diaphragm, and a fluid fuel conduit, of which said diaphragm forms one wall, communicating with said tube.

2. The combination with an atomizer tube, a casing mounted thereon, a flexible diaphragm in said casing, and a clearer needle secured to said diaphragm and extending into said tube, of a fluid fuel conduit extending across said diaphragm and communicating with said tube, and an extension from said needle working through an opening in the wall of said conduit.

3. The combination with a pressure chamber, and a pressure pipe connected therewith, of an atomizer tube within said chamber, a liquid fuel supply pipe communicating with said atomizer tube and furnished with a pressure controlled valve, and a connection between said valve controlling means and the pressure pipe.

4. The combination with a burner comprising a pressure chamber, and an atomizer tube, of a liquid fuel supply pipe communicating with the atomizer tube and having a valve seat, a casing connecting with said pipe, a diaphragm within said casing provided with a valve for said seat, and a pressure supply pipe connected with said pressure chamber 110 and with the diaphragm casing.

In witness whereof I affix my signature in presence of two witnesses.

BENJAMIN F. JACKSON.
